CLEANING APPARATUS

William J. Elvin, Frostburg, Md., Elmer R. Stahl, Meyersdale, Pa., Raymond D. Reel, Keyser, W. Va., and Joseph H. Duckworth, Lonaconing, Md., assignors to Celanese Corporation of America, a corporation of Delaware

Application November 8, 1940, Serial No. 364,830

6 Claims. (Cl. 15—21)

This invention relates to cleaning apparatus, and relates more particularly to an apparatus for cleaning textile bobbins.

An object of our invention is the provision of means for cleaning textile bobbins used for packaging yarn or thread.

Another object of our invention is to provide an automatic bobbin cleaning means.

A further object of our invention is the provision of means for the cleaning of textile bobbins which will reach all surfaces thereof.

A still further object of our invention is the provision of suitable means for trapping and removing the dust and dirt loosened from the bobbins by the cleaning means.

Other objects of our invention will appear from the following detailed description.

In cleaning textile bobbins it has been the usual thing to wipe them free from dirt and dust by hand. Although this method of cleaning is slow and tedious, the dust and dirt thereon must be removed. If the bobbins are used without cleaning, the yarn wound thereon becomes soiled with resulting irregularities in the cloth woven therefrom and, if the soiled cloth is not thoroughly scoured before dyeing, uneven dyeing may result. The removal of the dust and dirt deposited on the metal bobbins therefore becomes an important economic factor.

Our invention will now be described in detail with reference to the accompanying drawings, wherein there is shown a device for cleaning bobbins incorporating certain preferred embodiments:

In the drawings

Fig. 1 is a plan view of the device of our invention,

Fig. 2 is a view taken along line 2—2 of Fig. 1 showing in detail a single cleaning brush in position, the means for clamping the bobbin in position, the bobbin releasing means, the driving chains and sprockets, and the suction fan and ducts,

Fig. 3 is a detail view on a slightly enlarged scale showing the mechanism for moving the bobbins from the feed chute into position on the transport wheel,

Fig. 4 is a side elevational view of the mechanism in Fig. 3, taken along line 4—4 in Fig. 1,

Fig. 5 is a side elevational view, taken along the line 5—5 of Fig. 1, showing the bobbin feed chute,

Figs. 6, 7, 8 and 9 are detail views showing the manner in which each of the driven cleaning brushes shown in Fig. 1 becomes in contact with

the various portions of the bobbin to be cleaned, and

Fig. 10 is a detail view showing the counterbalanced bobbin supply cradle, the bobbin supply chute and the bobbin feed chute.

Like reference numerals indicate like parts throughout the several views of the drawings.

In the device of our invention, the bobbins 11 which are to be cleaned are first fed manually or by suitable mechanical means (not shown) into the top of a chute 12 (see Fig. 5) having a lateral opening 12' at the bottom thereof. In Fig. 5 a bobbin 11 is shown in position ready to be fed to a mechanism, generally indicated by the reference character A, which is adapted to carry bobbins successively to a number of cleaning stations hereinafter described. When the bobbins are placed in the chute 12, the first one is stopped by a detent 13 and the space at the lateral opening 12' will remain empty until a trapping mechanism, hereinafter described, is set in motion.

The detent 13 is pivoted on a pin 14 held in brackets 15 attached to the side of the chute 12. The detent 13 is held in operative position by an expansible spring 16 which bears against the side of the chute 12 and against an extension 13a integral with detent 13, the spring 16 being held in position by pins 17.

In order for the bobbin to be dropped to the discharge position adjacent the lateral opening 12', the detent 13 is disengaged to release the bobbin by the action of a cam 18 keyed to a rotating shaft 19 held in alignment by a bracket 20 fixed to the housing of the apparatus. The cam 18 is provided with a projection 18a which is adapted to depress an arm 13b integral with and substantially at right angles to detent 13 causing the same to move out of opening 21 in the wall of chute 12 and away from the trapped bobbins 40 whereby said bobbin is released and falls to the bottom of the chute. The movement of detent 13 away from the chute causes a detent 22 to rotate on its pivot 23 fixed to a bracket 24 and to move forward through another opening 25 in the wall of the chute thereby preventing any succeeding bobbins in the chute from falling on top of the bobbin which is now in position to be fed to the bobbin carrying mechanism. The play between detent 13 and detent 22 may be regulated as by a screw 26. After the release of arm 13b by the arm projection 18a, the spring 16 expands causing the detent 13 to reenter opening 21, the movement of detent 13 causing detent 22 to move out of opening 25 and the bobbin held by detent 22 falls until it is stopped by detent 13,

50

When the bobbin 11 has been dropped to the bottom of the chute within lateral opening 12, it is ready to be moved to the bobbin carrier A. This bobbin carrier comprises two spaced parallel plates 27 keyed to a shaft 27' and adapted to be rotated thereby. Each plate is provided with slots 28 corresponding to and aligned with the slot of the opposed plate. Each pair of aligned slots are adapted to receive a bobbin, as shown in Figs. 1, 2 and 3, and to carry them by the several cleaning stations.

Automatic means are provided for moving a bobbin 11 into aligned slots 28 in plates 27. As shown in Figs. 3 and 4, this means comprises a bifurcated arm 29 pivoted at 30 to a rod 31. The arm 29 is provided with an integral extension 29' by which said arm 29 is operatively connected to a rod 32 through an arm 33 which is pivotally attached to rod 32 by means of pins 34 and 35. The rods 31 and 32 are supported by and pass through blocks 36 and 37 fixed to a shelf 37' in the housing of the apparatus. The arm 29 is operated to move the bobbins from the chute to the bobbin carrier by means of a pair of cams 38 and 39 keyed to a shaft 40. Cam 38 operates on a cam follower 41 carried in a bifurcated end of rod 31 and cam 39 operates on cam follower 42 similarly carried in a bifurcated end of rod 32. As the cam 38 causes rod 31 to move forward, cam 39 also moves rod 32 forward causing arm 29 to enter chute 12. As rod 31 reaches the limit of its forward motion, rod 32 continues to move an additional distance forward under the action of cam 39, causing arm 29 to pivot at 30 and move horizontally, thereby registering bobbin 11 in aligned slots 28. As cam 38 turns, the movement of arm 29 and rod 31 is reversed by springs 43 and 44 anchored to posts 45 and 46 at one end and pulling on a rod 47 set in rod 31 at the other. The movement of rod 32 is likewise reversed, as cam 39 turns, by a second pair of springs (not shown) anchored below springs 43 and 44 on posts 45 and 46 and pulling on a rod 47 set in rod 32.

As the bobbin 11 registers with slots 28, it is caught by centering clamps 48 which are caused to act by expansible springs 49. The clamps 48 are held open by stationary cam 50 until the rotation of the bobbin transport plates 27 carries the cam follower 51 beyond the stationary cam 50, thus permitting the springs 49 to expand and close the clamps on the bobbin. Stop means such as adjustable stop screws may be provided to limit the extent of the closing movement of the clamps 48, thereby preventing too close a gripping of the bobbin and thus insuring the free rotation of the bobbin while held in the clamps 48 during the cleaning operation. Said means may be provided on the bobbin transport plates 27. The clamps 48 are supported by brackets 52 to which they are pivotally attached by pins 53, brackets 52 being held on the bobbin transport plates 27 as by screws 54. The stationary cam 50 is supported by a spider 55.

The bobbin transport plates 27 are set on a shaft 27' rotated by a chain 56 meshing with sprocket wheels 57 and 58 which are in suitable geared ratio. Sprocket wheel 58 is keyed on to shaft 27' and wheel 57 is keyed on to shaft 59 which is driven by a motor 60 through suitable gearing enclosed in gear box 61. As shown in Fig. 1, the bobbin trapping and feeding mechanism in Fig. 5 is operated by a chain 62 driving the shaft 19 through a sprocket wheel 63, the power for driving the chain 62 being taken from 75

the drive shaft 59. In like manner, cams 38 and 39 which operate to move the forked arm 29 and register the bobbins with the aligned circular slots 28 are driven by a chain 63 connected to the shaft 40 by a sprocket wheel 64 and to drive shaft 59 by another geared sprocket wheel 65.

After the bobbin 11 has been clamped into position it is carried to the several cleaning stations, which comprise a series of angularly disposed revolving brushes. The first brush coming in contact with the bobbin is the brush 66 which cleans the outer surface of the top flange of the bobbin, the second brush 67 cleans the outer surface of the bottom flange of the bobbin, the third brush 68 cleans the upper inner surfaces of the bobbin and the fourth brush 69 cleans the lower inner surfaces. The combined action of the brushes acting in sequence serves to clean all the surfaces and the action of the brushes will be more particularly described in connection with the brush 67.

As shown in Figs. 1 and 2, brush 67 is driven by a shaft 70 connected to a suitable motor 71. The motor 71 and brush shaft supporting posts 72 and 73 are mounted on a platform 74 which is pivoted on a post 75 for horizontal movement and on a pin 76 set in brackets 77 for suitable vertical movement, the auxiliary movement enhancing the action of the brush. Platform 74 is given a reciprocating vertical movement by a double-acting cam 78 operating on a cam follower 79 mounted in brackets 80. The cam 78 is keyed on a shaft 81 which is turned by a chain drive 82 meshing with a sprocket 83 set on shaft 81, said shaft being journaled in a bearing 84. Chain 82 is moved by a sprocket 85 keyed on driven shaft 59. The reciprocating horizontal movement of the platform 74 is produced by the cam 73, the periphery of which operates on cam follower 86 attached to the stud 86' depending from the underside of platform 74. The platform 74 and the brush 67 are returned after each displacement by a spring 87 attached to a stud 88 at one end and to a post 89 integral with a channel 90 at the other end. This reciprocating vertical and horizontal motion of the brush 67 thoroughly cleans the outer surface of the lower flange of the bobbin 11. An air duct 91 catches the dirt which is brushed loose, the suction being provided by an enclosed suction fan 92 rotated by a motor 93 supported on a bracket 94. The duct 91 leads to a main header 95 and the dust and dirt is discharged through a discharge duct 96. Platform 97 carrying brush 66 also describes a reciprocating horizontal motion produced by a cam 98 rotating in contact with a cam follower 99 and is returned after each displacement by suitable means. Brush 66 is not given any positive vertical reciprocating motion. Platform 97 is pivoted on a post 100 for horizontal movement and may be pivoted vertically on a pin 101 held in brackets 102 which are attached to the platform 97. The brush 66 is rotated by a suitable motor 103. Each of the brushes 66, 68 and 69 is also supplied with a suction duct communicating with the header 95 for carrying away the dust and dirt loosened from the bobbins, the ends of said ducts 104, 105 and 106 being shown broken away in Fig. 1 and Fig. 2. A motor 107, suitably supported on platform 108 drives brush 68 and brush 69 is driven by motor 109 supported on platform 110.

When the bobbin 11 has passed each of the cleaning stations and is finally carried beyond brush 69, the cam follower 51 on the clamp 48

comes in contact with the stationary cam 50. This causes the clamps 48 to open and the clean bobbin drops to a discharge chute 111 from which said bobbin may be removed, or caused to slide into a convenient receiver.

The bobbins may be supplied for manual feeding to the bobbin supply chute 12 as shown in Fig. 10. A case full of soiled bobbins is set in a cradle 112 which is then raised and tipped by means of a counter-weight 113 so that the bobbins fall into a chute 114. The bobbins may then be removed through an opening 115 and manually fed to the bobbin supply chute 12.

It is to be understood that the foregoing detailed description is merely given by way of illustration and that many variations may be made therein without departing from the spirit of our invention.

Having described our invention, what we desire to secure by Letters Patent is:

1. A device for cleaning flanged bobbins comprising a series of centering clamps each adapted to engage the ends of the bore of the flanged bobbin and to leave the outer surfaces of the flanges free, means for moving said centering clamps together with the bobbins held thereby along a controlled path and a plurality of cleaning elements in said controlled path adapted to contact the surfaces of said bobbins.

2. A device for cleaning flanged bobbins comprising a series of centering clamps each adapted to engage the ends of the bore of a bobbin and to hold said bobbin freely rotatable and with the outer surfaces of its flanges free, means for moving said clamps together with the bobbin held thereby along a controlled path, and a plurality of cleaning elements in said controlled path adapted to engage the surfaces of said bobbins and to rotate said bobbins about their axis while cleaning the same.

3. A device for cleaning flanged bobbins comprising a series of centering clamps each adapted to engage the ends of the bore of a bobbin and to hold said bobbin freely rotatable and with the outer surfaces of its flanges free, means for moving said clamps together with the bobbin held thereby along a controlled path, and a plurality

of rotating brushes in said controlled path adapted to engage the surfaces of said bobbins and to rotate said bobbins about their axis while cleaning the same.

5. 4. A device for cleaning flanged bobbins comprising a series of centering clamps each adapted to engage the ends of the bore of a bobbin and to hold said bobbin freely rotatable and with the outer surfaces of its flanges free, means for moving said clamps together with the bobbin held thereby along a controlled path, a plurality of cleaning elements in said controlled path adapted to engage the surfaces of said bobbins and to rotate said bobbins about their axis while cleaning the same, and means for reciprocating at least one of said cleaning elements so as to facilitate the cleaning of said surfaces.

5. A device for cleaning flanged bobbins comprising a series of centering clamps each adapted to engage the ends of the bore of a bobbin and to hold said bobbin freely rotatable and with the outer surfaces of its flanges free, means for moving said clamps together with the bobbin held thereby along a controlled path, a plurality of rotating brushes in said controlled path adapted to engage the surfaces of said bobbins and to rotate said bobbins about their axis while cleaning the same, and means for reciprocating at least one of said brushes so as to facilitate the cleaning of said surfaces.

6. A device for cleaning flanged bobbins comprising a series of centering clamps each adapted to engage the ends of the bore of a bobbin and to hold said bobbin freely rotatable and with the outer surfaces of its flanges free, means for moving said clamps together with the bobbin held thereby along a controlled path, a plurality of cleaning elements in said controlled path adapted to engage the surfaces of said bobbins and to rotate said bobbins about their axis while cleaning the same, and means for reciprocating the cleaning elements in at least two directions.
